LOOM ATTACHMENT

Ernest C. Geier, White Plains, N. Y., assignor to
 Duplan Silk Corporation, New York, N. Y., a
 corporation of Delaware

Application July 23, 1938, Serial No. 220,840

1 Claim. (Cl. 28—19)

The present invention relates to a loom attachment and particularly relates to a loom attachment for disposing of exhausted quills and for denuding said quills of the residual filler or weft thereon.

In the usual type of loom, particularly of the automatic variety, it is necessary for the operator or weaver when the shuttle is exhausted to remove the quills from the shuttle and place such quills in a box or receptacle at the front of the loom.

Usually, it is also necessary for the weaver to remove the residual filler or weft still remaining on the quill.

At intervals assistants usually come along the row of looms and remove the exhausted cops or quills and return them to the winding room where they are rewound with weft or filling and where they are separated according to the color or according to their particular weft or filler which they are designed to carry.

With automatic looms costing a relatively large amount of money and designed primarily to save the operator's time and primarily advantageous in that they enable the operator or weaver to attend a larger amount of looms than would otherwise be possible, this operation of removing the residual filling or weft from the quills consumes considerable time and also slows up the operation and detracts from the desirable effects of the automaticity of the loom.

It is, therefore, among the objects of the present invention to provide an improved loom attachment for automatic looms but which is also designed for other types of looms in which the quills from exhausted shuttles may be substantially or partly automatically denuded of the filler weft and at the same time disposed of at a suitable place and position where they may be readily collected in different colors without interference with the weaver or operator of the looms.

Another object of the present invention is to provide an improved quill disposer which will be susceptible of ready association with the loom without substantial reconstruction thereof and without interference with the normal operation and control of the weaving operation.

Other objects will be obvious or will appear during the course of the following specification.

In accomplishing the above objects, it has been found most satisfactory to provide a plurality of conduits or tubes preferably one for

each particular type of quill or cop into which may be dropped the exhausted quill or cop.

At the lower ends of the tubes or conduits may be positioned collector boxes in which the respective exhausted quills or cops may be collected.

With the usual type of automatic loom having an elevated fresh quill or cop supply it is generally most desirable to position the inlet to the tubes adjacent such supply board and then to have the tubes incline downwardly toward the rear of the loom where the collector boxes may be positioned and where the exhausted quills or cops may be removed by the collector boys without interference with the weavers.

To remove the residual filler or weft upon the quills the loose end of the residual filler or weft may be clipped or tied at the inlet end of the tube and the tube may then be dropped through the tubes which would cause such filler to unwind.

Since the filler usually may be longer than the length of the tube, it has been found most satisfactory to provide a rotating swift cone or other device which will have the effect of catching the filler and winding it up upon the cone swift or other device from which it may be readily removed without difficulty.

This will position the quills or cops without residual filler in the collector boxes at the rear of the loom and make the collection operation and the replenishment of such quills much simpler.

In the drawings which show several of the various possible embodiments according to the present invention but to which the invention is by no means restricted, since many changes or alterations may be made therein all within the scope of the present invention or without departing from the spirit thereof:

Figure 1 is a perspective view of the loom construction showing the manner of assembling and positioning the attachment of the present invention thereon;

Figure 2 is a side elevational view of the loom showing the attachment of the present invention and particularly the device for taking up the excess and residual weft;

Figure 3 is a fragmentary perspective view of the driving mechanism.

Referring to Figure 1, the loom is provided with the frame 10, with the take up roll 11, with the control levers 12, with the lay 13, the heddles 14, the heddle control mechanism 15, 16 and 55

17, with the shuttle boxes 18, with the shuttle magazines 19, and with the automatic shuttle changing mechanisms 20 and 21.

To the rear of the loom is positioned the main shaft 22, which passes through the clutch 23 and which drives the auxiliary shaft 24 provided with the hand wheel 25.

Above the magazines 20 is positioned the fresh quill carrier 26 carrying the fresh quills 27.

10 Ordinarily, with the type of loom shown in Figure 1, when a shuttle is exhausted, it would be pressed outwardly upon the shelf 28, into the box 29, where the operator will remove the exhausted quill and replace it by a fresh quill 27.

15 It is to the disposal of these exhausted quills that the present invention is most particularly directed.

As shown best in Figure 1, from the bar 30 supporting the board 26 extends a rectangular frame structure having the front member 31, the back member 32 and the bars 33 and 34. From the bar 34 extends the support bar or rod 35 to which is clipped at 36 and 37 the upper ends of the tubes 38 and 39, the mouths 40 and 41 of which are positioned closely adjacent the board 26, as indicated.

These tubes 38 and 39 extend downwardly and rearwardly to the collector box 42 having the compartments 43 and 44 in which the exhausted 30 quills are disposed.

Usually separate tubes 38 and 39 are provided for each different type of webt which is employed so that in each compartment 43 and 44 there will be collected one type of quill each one of 35 which is to receive the desired type of filling.

If desired, a clip or hook might be provided adjacent the upper ends of the tubes 38 and 39 upon which the end of the filling might be tied, so that the filling will be unravelled or unwound 40 from the quill as the quill drops from the tubes 38 and 39.

However, if the length of the tubes 38 and 39 is not sufficient to unravel all of the residual webt or filling, it has been found preferable to 45 provide an unwinding device such as a swift, a cone or some other device for winding up the residual filling or webt.

In the construction shown, a cone 45 is rotatably mounted at 46 upon the forward extension 50 of the side bar 34.

The cone is provided with the pulley 48 which carries the belt 49 connected to the pulley 50.

The pulley 50 is rotatably mounted upon the bar 51 supported upon the bar 34 at 52.

55 The rotating shaft 53 is rigidly connected to the pulley 50 and also to the pulley 54 which is mounted upon the bar 55 connected to the bar 33 at 56.

The pulley 54 carries the belt 57 which is driven 60 by the pulley 53 upon the shaft 59 which carries the hand wheel 25 and which is driven by the shaft element 24.

In operation, when the operator removes an

exhausted shuttle from the box 29, he first places the new quill in position and replaces the shuttle in the magazine 19. Then the loose end of the residual webt is pressed on to the revolving cone 45 which will pick it up and the quill, depending upon whether it is a left or right turn and also depending upon the character of the webt filling is dropped through one of the tubes 38 and 39 into the collector box 42.

If the amount of residual webt or filler left 10 on the quill is greater than the length of the tubes 38 and 39 the revolving cone 45 will unwind the remaining webt leaving the denuded quill in the basket 42. The webt or filler thread on the cone 45 may then be easily removed.

15 From the collector box 42, the exhausted quills are now denuded of their residual webt or filling, and they may be collected by boys passing behind the looms where they will not interfere with the weavers.

20 It is apparent that the specific illustrations shown above have been given by way of illustration and not by way of limitation and that the structures above described are subject to wide variation and modification without departing 25 from the scope or intent of the invention, all of which variations and modifications are to be included within the scope of the present invention.

20 What is claimed is:

In a disposal system for exhausted quills for use with an automatic loom of the shuttle changing type having a shuttle changing box at one side of the loom, an elevated board at said side of the loom carrying fresh quills, a 30 raceway for receiving exhausted shuttles below said box at said side of the loom, and a receiving box to receive said exhausted shuttles from said raceway; said system including two tubes having elevated inlet ends substantially above 35 said raceway and closely adjacent said elevated board at the upper front portion of the loom and having outlet ends at the rear of said loom adjacent the floor, said tubes extending obliquely downwardly along said side of the loom, a collector box at the rear of the loom having a plurality of compartments receiving the outlet ends of said tubes, one outlet end being positioned in each compartment, the exhausted quills being collectible from said collector box at the rear of 40 the loom without interference with the weaver working at the front of the loom, and means located substantially above said raceway and positioned at the inlet ends of the tubes to remove the residual filling from the exhausted quills 45 which may be placed in said inlet ends, said last mentioned means having an element to grasp the end of said residual filling when said quills are placed in the inlet ends of said tubes and to remove said exhausted filling from said exhausted 50 quills when said exhausted quills are falling through said tubes.

ERNEST C. GEIER.
